W. A. TURBAYNE

ELECTRIC REGULATOR

Filed July 17, 1919

Wm. A. Turbayne
INVENTOR.

WITNESS:

Burr H. Caldwell
Raef Munden

BY
Rogers and H. Van West
ATTORNEY.

UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

ELECTRIC REGULATOR.

Application filed July 17, 1919. Serial No. 311,454.

To all whom it may concern:

Be it known that I, WILLIAM A. TURBAYNE, a citizen of the United States, residing at Niagara Falls, in the county of Niagara and State of New York, have invented new and useful Improvements in Electric Regulators, of which the following is a specification.

The present invention relates to electric regulators.

In electrical regulators, difficulty has been encountered due to the fact that if the regulator is made sensitive to small changes, it will have a hunting action when more considerable changes occur.

An object of the present invention is to provide an electric regulator which will be dead beat and will be sensitive to small changes.

A further object is to provide an electric regulator which is cheap to manufacture, sturdy in construction and reliable in service.

Referring to the accompanying drawings—

Figure 1 represents a plan view of one embodiment of the present invention.

Figure 2 is a view in side elevation.

A pair of magnetizable cores are represented by the numerals 1—1. Said cores may be arranged in parallel relation and may be provided with operating solenoids 2—2. Co-operating with adjacent ends of the cores 1—1 is an armature 3 which may be mounted upon a bell crank lever 4. Said armature 3 may be biased by a spring 5 to a position away from the ends of the cores 1—1. The position of the armature 3 will be determined by the attractive effect of the cores 1—1, which attractive effect of the cores 1—1, is opposed by the spring 5.

Co-operating with the right hand ends of the cores 1—1 is an armature 6 which may be wedge-shaped in conformation to correspond to the beveled ends of the cores 1—1. Said armature 6 may be mounted upon the lever 7 pivoted at the point 8. Said lever 7 is provided with an end portion 9 adapted to operate one end of a compressible pile 10, the other end of which may be fixed. It will be apparent without further description that when armature 6 is attracted toward cores 1—1, pressure will be released on

the compressible pile 10 whereby to increase the resistance of said pile. The lever 7 may be acted upon by the spring 11, which is mounted to oppose the attractive effect of the cores 1—1 whereby said spring 11 will bias the lever 7 to compress the pile 10. A dash-pot 12 is provided having one of its elements connected to the lever 7 whereby to damp the movement of said lever 7 and thereby damp the operation of armature 6. Bell crank lever 4 and armature 3, which co-operate with the left-hand ends of the cores 1—1, should be undamped, whereby to be instantly responsive to changes in the attractive effect of cores 1—1, which attractive effect will be responsive to the magnetizing effect of the solenoids 2—2.

A mode of operation of the above described embodiment of the present invention will be substantially as follows: The solenoids 2—2 will be connected to an electric circuit to the functions of which it is desired that the compressible pile 10 shall respond. When less than a predetermined magnetizing current is flowing in the solenoids 2—2, the armatures 3 and 6 will both be held away from the cores 1—1 whereby reluctance of the magnetic circuit comprising cores 1—1 and armatures 3 and 6 will be a maximum. When a predetermined magnetizing effect of the solenoids 2—2 is exceeded, the armature 3 being undamped, will instantly respond to decrease the reluctance of the magnetic circuit of the regulator. Armature 6 being damped by dash-pot 12, will act subsequently to the operation of the armature 3 and will assume a new position whereby to relieve pressure on the compressible pile 10. While lever 7 is assuming its new position, thereby altering the reluctance of the magnetic circuit, the armature 3 will gradually move away from the cores 1—1, whereby a position of balance will be reached without any hunting. The regulator will accordingly be dead beat. The parts will be so designed and adjusted that armature 3 will never contact with cores 1—1, in service, but will always be readily available to adjust the reluctance of its magnetic circuit. In some cases, as for instance, in the case of a compressible pile of relatively great effective length, it may be preferred to omit the dash-

2
pot 12. In either case, the reluctance changing member 3 operates practically instantaneously upon changes in magnetizing effect of the solenoids 2, 2 to cause a magnifying effect upon the operating member 7.

In service, the compressible pile 10 will be so connected in circuit that changes in the resistance thereof will cause a response in the electrical circuit, the function of which 10 it is desired to control. The fact that the armature 3 is undamped, will cause a practically instantaneous setting of the magnetic reluctance of the regulator whereby the lever 7 may operate in response to either very considerable or very small changes, moving directly and with certainty to the position for exerting the proper pressure upon the compressible pile.

As noted above, the reluctance varying 20 member 3 will assume different positions for reluctance adjusting functions, between the extreme positions, due respectively (1) to insufficient magnetizing effect to overcome spring 5, or (2) to high magnetizing effect 25 which holds member 3 close to, but spaced from cores 1, 1. This mechanism is to be distinguished from reluctance varying means wherein a reluctance varying member occupies one of two alternate positions, to 30 wit, that producing maximum reluctance and that producing minimum reluctance. According to the present invention, an infinite number of positions between the extremes above noted may be had. As shown 35 in the drawing, the spring 5 is adjustable whereby to adjust the value at which member 3 shall begin its reluctance varying functions.

One example of the many uses for the present invention is the following. The mechanism of the present invention may be used 40 for varying the field excitation of a variable speed generator which is used for storage battery charging purposes. Said mechanism may be connected to respond to current changes in the charging mains. The spring 5 may be adjusted to a value whereby the member 3 would not respond until the rising C. E. M. F. of the battery resulted 45 in the raising of the voltage across the mains to a predetermined value. Said member 3 would thereafter gradually decrease the reluctance of the magnetic circuit, resulting in a gradually increasing effectiveness per 50 ampere turn of solenoids 2, 2, resulting in a tapering current to the battery.

The armature 6 may be provided with a magnetic adjusting member 13. Said member 13 is provided with a pair of ears 14 of 60 magnetic material. Said ears 14 should be capable of being bent toward or away from one another, whereby to increase or decrease the reluctance of circuit comprising cores 1, 1 and armatures 3 and 6. By the simple 65 expedient, therefore, of bending ears 14, 14,

the magnetic reluctance may be nicely adjusted. For this purpose the member 13 may be of pliable magnetic material.

What I claim as new and desire to secure by Letters Patent of the United States, is— 70

1. In an electric regulator, a pair of cores adapted to be magnetized, a pair of armatures adapted to complete a magnetic circuit for said cores, said armatures being biased away from said cores, a compressible 75 pile, operating means for said pile, said operating means being operable by one of said armatures, said last mentioned armature being damped, the other of said armatures being undamped. 80

2. In an electric regulator, a pair of magnetizable cores, a pair of armatures adapted to complete a magnetic circuit for said cores, one of said armatures being undamped, but being provided with resilient means opposing the attractive effect of said cores, whereby to vary the effect of said armature in affecting the reluctance of said magnetic circuit, the other of said armatures being damped, a compressible pile, and means operable by said other armature for operating said pile. 85 90

3. In combination, a variable resistance element, operating means therefor, electro-magnetic means for controlling said operating means, said electro-magnetic means being provided with means for rendering said operating means dead beat, comprising quick acting means for changing the magnetic reluctance of said electro-magnetic 100 means. 95

4. In combination, a variable resistance element, operating means therefor, electro-magnetic means for controlling said operating means, and means for gradually changing the reluctance of said electromagnetic means comprising means responsive to the magnetization of said electromagnetic means. 105

5. In combination, electromagnetic means, a compressible pile, pile-operating means controlled by said electromagnetic means and quick acting means responsive to said electromagnetic means for varying the magnetic reluctance of said electromagnetic means, said pile operating means being provided with means to delay the action thereof. 110 115

6. In combination, a compressible pile, a pair of magnetizable cores arranged in parallel relation to said pile, a pair of armatures adapted to complete a magnetic circuit with said cores, said armatures being located at opposite ends of said cores in a position to be attracted toward the end faces of said cores, said cores being arranged horizontally whereby said armatures will not be readily responsive to sudden jolts in a vertical direction, one of said armatures being undamped and being adapted to vary the reluctance of said magnetic circuit, the other of said armata. 120 125 130

- tures being damped and being provided with means for compressing said pile.
7. In a regulator, in combination, a compressible pile, a magnetic circuit, said circuit having a quick acting member adapted to quickly adjust the magnetic reluctance of said circuit, said circuit having a damped member provided with means for operating said pile.
- 10 8. In a regulator, in combination, a compressible pile, a magnetic circuit, said circuit having a quick acting member adapted to quickly adjust the magnetic reluctance of said circuit, said circuit having a damped member provided with means for operating said pile, said damped member being provided with magnetic means for adjusting the reluctance of said circuit.
9. In an electric regulator, a pair of cores adapted to be magnetized, a pair of armatures adapted to complete a magnetic circuit for said cores, said armatures being biased away from said cores, a compressible pile, operating means for said pile, said operating means being responsive to one of said armatures, said last mentioned armature being damped, the other of said armatures being undamped, said damped armature being provided with magnetic means for adjusting the reluctance of said circuit.
10. In a regulator, in combination, a pair of cores, an armature co-operating with adjacent ends of said cores, said armature having magnetic means for adjusting the magnetic reluctance between said armature and said cores, a compressible pile and means operated by said armature for controlling said pile.
11. In a regulator, in combination, a pair of cores having beveled ends, an armature having beveled ends co-operating with and corresponding to the beveled ends of said cores, said armature having a magnetic member having ears which may be moved to change the reluctance between said cores and said armature, a compressible pile and means operated by said armature for controlling said pile.
12. In a regulator, in combination, a variable resistance element, a magnetic circuit, said circuit having a member for automatically gradually adjusting the magnetic reluctance of said circuit, said circuit having a member provided with means for operating said resistance element.
13. In combination, a variable resistance element, operating means therefor, electromagnetic means for controlling said operating means, said electromagnetic means being provided with means for rendering said operating means dead beat, comprising means for gradually changing the magnetic reluctance of said electromagnetic means.

In witness whereof, I have hereunto subscribed my name.

WILLIAM A. TURBAYNE.
